UNITED STATES PATENT OFFICE

CHARLOTTE E. ANSLEY, OF MINNEAPOLIS, MINNESOTA

GARMENT

Application filed June 6, 1927. Serial No. 196,778.

This invention relates to women's and children's garments and particularly to combination garments of the type used for underwear, bathing suits, dress and underwear combinations etc.

It is the object of this invention to provide a novel garment of improved construction which will combine the various features of a number of garments now commonly worn by women and children in one unitary structure.

To this end, the invention consists in the novel parts and novel combinations of parts defined in the claims and hereinafter described in connection with the accompanying drawings, wherein like reference characters refer to the same or similar parts throughout the various views and, in which,

Fig. 1 is a plan view of a pattern for the garment;

Fig. 2 is a perspective view illustrating a girl wearing the made-up garment, certain of the parts of the garment being broken away and certain of the parts being shown in section;

Fig. 3 is a top plan view of the made-up garment;

Fig. 4 is a vertical section taken through the medial portion of the front and back of the garment on the line 4—4 of Fig. 3 as indicated by the arrows;

Fig. 5 is a vertical sectional view through the top portion of the garment taken on the line 5—5 of Fig. 3, as indicated by the arrows;

Fig. 6 is a perspective view of the garment showing the slip and brassière portions of the garment raised upwardly from the top of the garment;

Fig. 7 is a perspective view of the garment showing the slip portion of the garment raised upwardly from the top thereof and the brassière portion of the garment extending downwardly in wearing position, one corner of the front flap of the brassière portion being raised;

Fig. 8 is a perspective view showing the parts of the garment in wearing position with the exception of the lower part of the slip portion which is raised upwardly from adjacent the middle of the same;

Fig. 9 is a horizontal section taken on the line 9—9 of Fig. 4, as indicated by the arrows;

Fig. 10 is a horizontal section taken on the line 10—10 of Fig. 4, as indicated by the arrows, and

Fig. 11 is a perspective view of a tubular cloth from which the garment may be made if desired.

In describing and claiming the present invention, certain verbiage will be used throughout, which unless otherwise specified, will have the following meaning. The word "slip," unless otherwise designated, shall be taken to mean either such a garment as a princess slip, which is a name used in the garment trade to designate a straight hanging garment adapted to extend from the bust of a wearer to adjacent the knees of the wearer and which has a straight lower edge and is used as a protective garment in the nature of a petticoat, or the word "slip" may mean an outer dress, an outer bathing garment or other garments which are constructed similar in most respects to a princess slip. The word "drawers," unless otherwise designated, shall be taken to include any type of woman's drawers such as stepins, teddies, bloomers, pants, panties etc. The words "shoulder straps" shall be taken to mean straps which are adapted to be extended over the shoulders of a wearer to support a garment therefrom. The word "brassière" shall be taken to mean a garment in the nature of a brassière, camisole, bandeau, or other types of breast supporter. The word "shirt," unless otherwise designated, shall be taken to mean a vest, shirt or similar garment commonly worn by women next to the skin and adapted to extend from adjacent the bust to a point below the hips. The words "shadow hem" shall be taken to mean a hem commonly provided in the lower portion of a garment in the nature of women's underwear, dresses or skirts to prevent light from shining through the garment to expose the contour of the figure of the wearer to view.

Referring to the drawings, the garment is preferably formed from a single long tubular piece of cloth. This tubular piece may be

either made up as illustrated in the drawings, Figs. 1 to 10, from two similar flat rectangular blanks designated the front blank A and the back blank B respectively, the said blanks being stitched together at their sides from 5 their bottom edges to the top edges, or the tubular piece may be formed from tubular woven material as illustrated in Fig. 11, wherein the front portion of the material may be considered to comprise the front blank 10 C and the rear portion may be considered to comprise the rear blank D. Whichever type of tubular construction is adopted is immaterial and it will, of course, be understood that if desired the tubular piece may be formed 15 from more than two pieces of cloth. The material for the garment having been made up as described, the same is placed on a flat surface and is folded at the sides so that if the two piece construction is used, the front 20 blank A will lie directly on top of the rear blank B, while if the tubular construction illustrated in Fig. 11 is used, the front blank C will lie directly on top of the rear blank D. 25 If the tubular construction illustrated in Fig. 11 is used, the front blank C will be cut, folded and sewed in the same manner as the front blank A hereinafter described, while the rear blank D will be cut, folded and sewed in the 30 same manner as the rear blank B hereinafter described.

When the material for the garment has been placed as above described, the pattern for the garment will be laid out. Both front 35 and rear blanks A and B will be cut, folded and sewed the same except as hereinafter noted. It will thus be necessary to describe the pattern for only one blank as, for example, the blank A, whereupon variations from 40 the blank A in the construction of the blank B may be specifically noted.

A fold line 12 is laid out on the blank A transversely of the same and is spaced from the lower end of the blank a distance equal to 45 the desired length of the garment from the hips downwardly. This length is usually approximately equal to the distance from the hips to adjacent the knees of the person for whom the garment is being constructed hereinafter designated the wearer. A second transverse line 13 is laid out on the blank at 50 twice the distance from the lower end of the blank as the line 12, while a third transverse fold line 14 is laid out at a distance from the line 13 equal to the desired length of the garment from the top edge thereof to the bottom edge thereof. The distance between the lines 13 and 14 will approximately equal the height of the wearer from adjacent the knee to a 55 point above the bust. A fourth transverse line 42 is laid out on the blank at a distance spaced from the line 14 equal to the desired length of a brassière and shoulder straps to fit the wearer. The remainder of the garment upwardly 60 from the line 42 to the top of the garment will

be of a length equal to the length of a shirt adapted to fit the wearer; that is, the same will be of a length equal to the distance from above the bust of the wearer to a point slightly below the crotch of the wearer. Drawer 70 cuts are made in the blank longitudinally of the same adjacent the side edges thereof at 15 and adjacent the center of the blank at 16. Cuts 15 and 16 extend upwardly from a level above the line 12 to adjacent the line 13, the 75 cuts 16 being of slightly greater length than the cuts 15. A transverse cut 17 connects the two longitudinal cuts 16 to form drawer crotch strap portions 18, while transverse cuts 19 are made which connect the upper ends 80 of cuts 15 with the cuts 16 to form drawer flap portions 20. Longitudinal cuts 21 are made between the lines 14 and 42 to form shoulder strap sections 22, while transverse cuts 23 are made in the blank on the line 42 to form 85 brassière side sections 24 and flap section 25. Longitudinal cuts 26 are made at the top central portion of the blank to extend downwardly from the top and to form shirt crotch strap portions 27. The section of the blank between the lower end of the same and line 12 90 will be designated outer shadow hem section 28; the section between lines 12 and 13 and not included in the drawer crotch strap portions 18 or drawer flap portions 20 will be designated as inner shadow hem section 29; the section between the lines 13 and 14 will be designated slip section 30 and the section between the line 42 and the upper end of the blank will be designated shirt section 31. 95

After the two blanks A and B have been laid out and cut as above described, the garment may be made up. Pleats 32^a and 32^b folded on the longitudinal fold lines 33 coinciding in part with the cuts 21, as indicated 100 in Fig. 1, are formed in the blanks A and B respectively to provide two pleats, one at either side of the front of the garment and two pleats one at either side of the back of the garment. The pleats 32^a formed in front 110 blank A are folded outwardly towards the sides of the garment and stitched at their inner edges, while the pleats 32^b formed in rear blank B are folded inwardly towards the center of the back of the garment and are 115 stitched at their outer edges. Each of the shoulder strap sections 22 will accordingly be of a double thickness and the two thicknesses will be sewed together. The outer shadow hem sections 28 may now be folded 120 inwardly and upwardly on the fold lines 12, whereupon both the inner shadow hem sections 29 and the outer shadow hem sections 28 will be folded upwardly and inwardly on the fold lines 13. The sections 28, 29 and 30 125 will then be stitched together as folded, to assume the position as best illustrated in Figs. 2, 4, 8 and 10 of the drawings, leaving the drawer flap portions 20 and the drawer crotch strap portions 18 depending downwardly 130

from adjacent the center of the slip sections 30 of the garment. The two drawer crotch strap portions 18 will be provided with co-operating fasteners preferably of the snap type so that the two straps may be secured together to form a detachable crotch strap for a pair of drawers. The brassière side sections 24 and the brassière flap sections 25 will now be folded inwardly and downwardly on the fold lines 14, whereupon adjacent edges 21 of the sections 24 and 25 at the rear of the garment will be stitched together to form an integral main brassière section. The lower edges of the section so formed will be folded upwardly and stitched to form a draw string holder portion 34 for a draw string 35. The front flap section 25 will be provided with rows of spaced half snap fasteners 36 adjacent the side edges thereof, while the main brassière section will be provided with two or more rows of spaced half snap fasteners 37 adjacent each of the front edges 21, the half snap fasteners 36 being adapted to co-operate with the half snap fasteners 37 to secure the front flap section 25 to the main brassière section.

The shirt sections 31 will be swung downwardly through the opening in the front blank A between the front shoulder strap sections 21 until the shirt section 33 of blank A abuts the brassière sections of the blank B with the edge 23 of the shirt section adjacent the line 14 of the blank B and until the shirt section 31 of blank B abuts the brassière section of blank A with its top edge 23 adjacent the line 14 of blank A. When the parts of the garment are in this position, the upper edges of the various brassière, shirt and slip sections will be stitched at 38 and 39 to secure said parts together and to form a holder for an elastic band 40 which extends way around the top portion of the garment. The shoulder straps 22 formed from the rear blank B will then extend straight across from the rear side to the front of the garment without being twisted, while the strap sections 22 formed from the front blank A of the garment will extend from the front to the rear of the garment but will be twisted. To untwist strap sections 21 formed from the front blank A of the garment, the sections 21 will be cut from the front slip section 33 on the line 14 at 43 as shown in Fig. 1, whereupon the said front strap sections 21 will be untwisted and will be crossed over the rear shoulder strap sections 21 and secured to the upper edge of the front of the garment at points spaced sidewardly from the forward ends of the strap sections 22 formed from the rear blank B. A pair of crossed shoulder straps will accordingly be provided at either side of the garment and extending from the front upper edge of the garment to the rear upper edge of the garment, the lower ends of co-operating straps being spaced from each other at both front

and back. If desired, co-operating half snap fasteners 44 may be provided at the centers of co-operating straps 22, whereby the said straps may be releasably secured together at their centers. The shirt crotch strap portions 27 will be provided with co-operating half snap fasteners, whereby the same may be detachably connected to form a crotch strap of drawers formed integral with the shirt sections of the garment. Co-operating slits 41 are formed behind the pleats 32 in both the front slip and shirt sections which will form breast openings for a nursing mother. If desired, the various edges of the garment may be secured from unraveling by overcast stitching or stitched folds may be made at the various edges to prevent the unraveling of the goods.

The garment so constructed is now ready to be worn. The front and rear slip sections 33 will form a straight hanging slip with a straight lower edge. The outer shadow hem sections 28 will form a shadow hem at the bottom of the slip extending upwardly from adjacent the knees of the wearer to adjacent the waist of the wearer. If desired, various portions of the outer shadow hem sections 28 may be cut away at points where the inner shadow hem sections 29 overlie the same to provide a cooler garment. The inner shadow hem sections 29 will form an additional shadow hem at the bottom of the slip, while the sections 20 and 18 will form a pair of drawers cut away from the inner shadow hem and integrally connected with the slip of the garment. The main brassière section formed from the side brassière sections 24 and the back flap section 25, and the draw strings 35 together with the front flap section 25 will form a brassière. The shirt sections 31 will form a shirt while the lower portion of the shirt together with the drawer crotch strap portions 27 will form a second set of drawers integral with the shirt. The shoulder strap sections 22 will form crossed shoulder straps for supporting the garment from the wearer's shoulders. A garment will be provided which can be put on or taken off as a unit at the same time and will provide all the necessary undergarments for woman's wear.

A wearer can put on the garment by either slipping the same over her head or by stepping into the same. When the garment is being put on over the head of the wearer, the draw string 35 of the brassière is untied and the half snap fasteners 36 of the front flap of the brassière will be disengaged from the half snap fasteners 37. The crotch strap portions 18 and 27 will also be disengaged from each other. The garment will first be drawn over the head of the wearer until the same is in the position illustrated in Figure 6 with the brassière and slip extending upwardly from the top of the garment. The brassière can then be folded downwardly to

assume the position illustrated in Fig. 7, whereupon the draw string 35 is tied to cause the brassière to conform to the shape of the bust and the front flap 25 of the brassière is engaged with the main brassière section by means of the half snap fasteners 36 and 37. Due to the fact that several rows of half snap fasteners are provided on the main brassière section, the sides of the brassière may be adjusted when the parts of the brassière are secured together. If it is desired to use the drawers formed in the shirt either alone or with the drawers formed from the inner shadow hem of the garment, the crotch strap portions 27 will be united. If it is desired to use the drawers formed integral with the inner shadow hem of the garment either alone or with the drawers formed in the shirt, the strap portions 18 will be united. Due to the fact that the shoulder straps 22 of the garment are crossed over the shoulders of the wearer and that the ends of co-operating straps are spaced from each other, the straps will not slip off the wearer's shoulders but will retain their position during all circumstances and properly support the garment. The elastic 40 will also help to retain the garment in position. The brassière will support the bust of the wearer, while the slip will present an unbroken line from the bust to adjacent the knees of the wearer and will thus provide a slip of the true princess slip type now commonly being worn by women. The shadow hems at the bottom of the slip will act to prevent light from shining through the garment and exposing the contour of the figure of the wearer. By providing the drawers formed from the inner shadow hem as described, and by folding a second shadow hem outwardly from the top of the first hem between the lower portion of the slip and the first hem a pair of drawers will be formed which will not pull inwardly on the lower portion of the slip to break the even hanging appearance of the same. The pull on the drawers will be exerted against the medial portion of the slip extending around the hips of the wearer and this portion of the slip being of a size to just fit about the hips, the slip cannot be pulled out of shape and will retain its shape and will retain its smooth straight appearance. If desired, the wearer may put on the garment by stepping into the same instead of slipping the same over her head. When this is done it will not be necessary to detach the crotch strap portions of the garment.

One of the chief advantages of the garment is that when the same is worn the wearer can put on or take off corsets without necessitating a removal of any clothing. This may readily be done by detaching the crotch strap portions of the drawers formed in the shadow hem and by detaching the draw string 35 and the front flap 25 of the brassière and

raising the slip and brassière to the position illustrated in Fig. 6. The whole garment may be conveniently washed as a single unit and thus labor and expense will be saved in the usual laundrying operation. Instead of using the slip of the garment as a straight princess slip, the same may be used as an outer dress garment for women or children, or the slip may be slightly modified to form an outer portion of the garment into a bathing garment, a nurse's uniform, a riding habit or similar garments. The construction of the drawers in both the slip and in the shirt may be considerably varied as desired to form any type of bloomers, stepins, teddies, panties, pants etc. The nursing openings 41 may be left out if desired, but when incorporated in the garment they will be found very convenient and handy for nursing mothers and will be unobservable from the outer side of the garment due to the pleats 32.

The garment will present a neat and attractive appearance and may be very readily cut out and put together. The various steps in making up the garment may be considerably varied if desired and modifications in the cuts and folds in the garment may be made if desired. If desired, certain portions of the garment may be left out entirely to allow other parts to be used alone. The quantity of material used in the complete garment is much less than that used in the various garments for which the present garment may be substituted.

It will, of course, be understood that various changes may be made in the form, details, arrangement and proportions of the various parts without departing from the scope of the present invention, which, generally stated, consists in the matter shown and described and set forth in the appended claims.

What is claimed is:

1. An integral combination garment adapted to be put on and worn as a unit and including in combination a slip, a brassière and a shirt all secured together adjacent the top edges, the shirt being innermost and depending downwardly and the brassière depending downward between the slip and the shirt.

2. An integral combination garment adapted to be put on and worn as a unit, comprising a slip portion, an inner shadow hem portion folded upwardly from the lower end of said slip portion and an outer hem portion folded downwardly from the upper edge of said inner hem portion and extending between said slip portion and said inner hem portion, said hem portions being secured to said slip portion adjacent their upper edges and said inner hem portion having a pair of drawers formed therefrom.

3. A woman's garment comprising a slip adapted to fit the body of the wearer to extend from adjacent the bust to adjacent the knees, said slip being inwardly folded at the

lower end thereof to extend upwardly above the crotch of the wearer and form an inner shadow hem and then being outwardly folded from the top of said inner shadow hem to extend downwardly therefrom between the same and the lower portion of the slip to form an outer shadow hem, said inner shadow hem having a pair of drawers formed therefrom.

4. The combination in a woman's garment of a slip and a brassière, said brassière being secured at its upper end to the upper edge of said slip and extending downward therefrom, the said brassière having a main portion open on its medial front side and having a flap adapted to be detachably secured to the edges of said main portion adjacent said opening in a plurality of positions to vary the size of the brassière.

5. A woman's garment comprising a slip, an extension from said slip folded upwardly from the bottom therefrom to extend to a point above the crotch of the wearer, a second portion extending downwardly outwardly from said first mentioned portion between the same and said slip, said first mentioned portion being cut at its forward and rear side to form three flaps at both front and rear, the center flaps being of narrower width than the side flaps and being releasably securable together to form a crotch strap of a pair of drawers.

6. An integral combination garment adapted to be worn as a unit and formed from a single long tubular piece of cloth having a series of longitudinal cuts therein adjacent its upper end to form shoulder straps and a series of transverse cuts joining the upper ends of said longitudinal cuts to form flaps depending downwardly inside the main portion of the garment, said flaps being secured together to form a brassière and the main portion of said garment forming a slip.

7. The process of making a combination garment from a single piece of tubular cloth which consists in cutting slips adjacent the upper edge of the piece and longitudinally thereof to form shoulder straps, folding inwardly and downwardly the flaps left in the cloth after said straps are cut and securing said flaps together, whereby the main portion of said cloth will form a slip and said flaps will form a brassière.

8. The process of making a combination garment from a single piece of long tubular cloth which consists in cutting longitudinal slits in said cloth at spaced intervals above the center thereof to form shoulder straps, cutting transverse slits in said cloth between said straps adjacent one end thereof, folding said cloth so that the lower portion thereof forms a slip outwardly from said flaps and the upper portion of the cloth, and so that the upper portion of the cloth forms a shirt inwardly from said flaps, securing the side edges of said flaps together to form a bras-

sière between said slip and shirt and securing the upper edges of said slip, brassière and shirt together.

9. The process of making a combination garment which consists in providing a long tubular piece of cloth, folding the lower end of the cloth upwardly and inwardly to double the cloth adjacent its lower end, folding the doubled up portion upwardly and inwardly and cutting a pair of drawers from the innermost portion of the said cloth, whereby the outermost portion will form a slip, the medial portion will form a first shadow hem and the innermost portion will form a shadow hem from which drawers have been cut.

10. A woman's garment comprising a slip adapted to fit the body of the wearer to extend from adjacent the bust to adjacent the knees, said slip being folded upwardly from its lower end to form a shadow hem, and the upper portion of said shadow hem being folded downwardly, on a line adapted to extend above the crotch of the wearer, between the lower portion of the slip and the upwardly extending portion of the shadow hem to adjacent the bottom of the garment, the three layers of the garment being secured together on said fold line above the crotch of the wearer, and there being drawers cut from the innermost layer of said garment.

11. The process of making a garment from a single piece of cloth which consists in cutting slits therein adjacent the upper middle portion of the cloth to form shoulder straps and folding downwardly the upper portion of the cloth against the lower portion thereof, to form a shirt from the downwardly folded portion and a slip from the lower portion.

12. A woman's garment comprising a slip adapted to fit the body of a wearer to extend from adjacent the bust to adjacent the knees, said slip being folded upwardly from its lower end to form a shadow hem, and the upper portion of said shadow hem being folded downwardly on a line adapted to extend above the crotch of the wearer, the three layers of the garment being secured together on said fold line above the crotch of the wearer, and there being drawers cut from the innermost layer of said garment.

In testimony whereof I affix my signature.
CHARLOTTE E. ANSLEY.
